ATTORNEY

Patented Dec. 7, 1926.

UNITED STATES PATENT OFFICE.

EDMOND C. JOSEPH, OF NEW ORLEANS, LOUISIANA.

SHADE AND CURTAIN ADJUSTING AND SUPPORTING MEANS.

Application filed August 25, 1924. Serial No. 734,089.

The object of my said invention is the provision of advantageous means whereby a window shade and curtain may be adjusted and adjustably fixed so as to afford a clear passage for overhead ventilation while obviating the draft and maintaining the privacy of an apartment.

To the attainment of the foregoing, the invention consists in the improvement as hereinafter described and definitely claimed.

In the accompanying drawings, forming part of this specification:—

Figure 1 is an elevation showing my improved means in use.

Figure 2 is a broken plan view of the same.

Figure 3 is a broken edge elevation of the improvement.

Figure 4 is an enlarged detail section on the line 4—4 of Figure 1.

Figure 5 is a plan view of the blank from which one of the slide members of the improvement is formed.

Figure 6 is a perspective of one of the lower brackets.

Figure 7 is a detail perspective of one of the latches comprised in the improvement.

Similar numerals of reference designate corresponding parts in all of the views of the drawings.

The window casing 1 is preferably arranged to contain sliding sashes 2 and is otherwise of the ordinary well known construction.

In accordance with my invention I provide on the faces of the side stiles of the casing 1 upper fixed brackets 3 and lower fixed brackets 4. These brackets serve to receive and hold upright bars 5 of angular cross-section, the said bars 5 being notched at 6. The offsets 7 of the lower brackets 4 are provided with circular apertures 8 for the reception of upright rock shafts 9 which are journaled in the offsets 7 and are provided at their lower ends with handles 10. At 11 the rock shafts 9 are toothed as shown in Figure 4.

The vertically movable slide members 12 of my improvement are preferably, though not necessarily, formed respectively of a blank such as designated by 12^x in Figure 5, each of the said slide members being of rectangular form and being provided in their upper and lower walls with annular apertures 13 for the passage of the bars 5 and being also provided with outer overhanging portions 14 which serve for the connection

of the upper ends of the shafts 9 and terminate in pendent resilient portions 15 which tend to spring inwardly or toward each other.

Guided in the outer walls of the slideable members 12 are latches 16, beveled at 17 to engage the notches 6 of the bars 5 and having racks 18 in mesh with the teeth 11 of the shafts 9. The outer ends of the said latches 16 are reduced at 19 and disposed in apertures in the arms 15 which arms tend to press the latches 16 inwardly and yieldingly hold the said latches 16 against casual outward movement.

Interposed between and appropriately connected to the slideable members 12 is a rod 20, Figure 2, designed and adapted to prevent turning of the said members 12 horizontally about their axes, and also designed to assist in the vertical movements of the members 12 as a unit.

The slideable members 12 are provided with the usual aperture and notch, respectively, for the reception of the end bearings of a shade roller 21, and it will also be noted that the slideable members 12 are provided with hooks 22, designed for the engagement and support of a curtain pole 23 shown by dotted lines in Figure 2.

The upper ends of the shafts 9 are journaled in and connected to the overhanging portions 14 of the slideable members 12, and from this it follows that through the medium of the shafts 9 the slideable members 12 and the shade and curtain supported thereon may be expediently and easily lowered. The slideable members 12 are adjustably fixed to the bars 5 by the latches 16, and from this it follows that precedent to raising or lowering the slideable members 12 and the shade and curtain, the said shafts 9 must be turned about their axes so as to withdraw the latches 16 from engagement with notches of the bars 13. Then when the slideable members 12 are positioned as desired, the shafts 9 are released whereupon the resilient terminals 15 of the members 12 will press the said slideable members 16 into notches of the bars 5.

It will be apparent from the foregoing that through the medium of my improvement a shade and curtain may be lowered so as to afford adequate overhead ventilation and at the same time prevent the passage of drafts in an apartment, and without affecting the privacy of the apartment.

I have specifically described the preferred

embodiment of my invention in order to impart an exact understanding of the said embodiment. I do not desire, however, to be understood as confining myself to the specific construction and relative arrangement of parts in the present disclosure inasmuch as my invention is defined by my appended claim within the scope of which changes may be made without affecting my invention.

Having described my invention, what I claim and desire to secure by Letters Patent is:

A device of the character described including spaced fixed brackets, an upright bar between said brackets, a slide member mounted for adjustment on the bar and including a pendent resilient portion spaced from the body of the slide member, said up-right bar

having spaced notches, a latch member having reduced end portions, one of which is 20 slideable through one wall of the slide member and beveled for engagement with the notches in said up-right bar, the other reduced end of said latch being mounted in the resilient pendent portion whereby to normally retain the beveled portion in operative position, a rack formed on said latch member, and a rock shaft supported parallel with the upright bar and having teeth for engagement with the rack whereby to actuate said rack to release the slide member and said rock shaft being longitudinally movable as and for the purpose set forth.

In testimony whereof I affix my signature.

EDMOND C. JOSEPH.
